[57] CLAIM

The ornamental design for a space amusement ride, substantially as shown and described.

DESCRIPTION

FIG. 1 is a perspective view of a space amusement ride showing my new design;

FIG. 2 is a side elevational view thereof, the side opposite being substantially a mirror image;

FIG. 3 is a top plan view thereof;

FIG. 4 is a cross-sectional view thereof taken along line IV—IV in FIG. 2; and

FIG. 5 is a cross-sectional view thereof taken along line V—V in FIG. 2.
